US0D1013367S

(12) **United States Design Patent** (10) Patent No.: **US D1,013,367 S**
(45) Date of Patent: ** Feb. 6, 2024

(54) **BACKPACK**

(71) Applicant: **Upper Echelon Products**, Austin, TX (US)

(72) Inventors: **Michael Joseph Zucco**, Austin, TX (US); **Grigory Alexandrovich Markov**, Nizhny Novgorod (RU)

(**) Term: **15 Years**

(21) Appl. No.: **29/791,636**

(22) Filed: **Jan. 25, 2022**

(51) LOC (14) Cl. **03-01**

(52) U.S. Cl.
USPC **D3/216**

(58) **Field of Classification Search**
